Primary Examiner—Dominic Simone
Attorney, Agent, or Firm—Banner & Allegretti, Ltd.[57] **CLAIM**

The ornamental design for a side element of a shoe upper, as shown and described.

DESCRIPTION

FIG. 1 is a side elevational view of a side element of shoe upper showing my new design;

FIG. 2 is a front elevational view thereof; and,

FIG. 3 is a cross-sectional view taken along the line 3—3 of FIG. 1.

The broken line showing of a shoe in FIGS. 1—2 is for illustrative purposes only and forms no part of the claimed design.
